CLAIM

The ornamental design for a headrest mount for electronic devices, as shown and described.

DESCRIPTION

FIG. 1 is a perspective view of a headrest mount for electronic devices;

FIG. 2 is a front view of the headrest mount for electronic devices shown in FIG. 1,

FIG. 3 is a bottom view of the headrest mount for electronic devices shown in FIG. 2,

FIG. 4 is a rear view of the headrest mount for electronic devices shown in FIG. 2,

FIG. 5 is a top view of the headrest mount for electronic devices shown in FIG. 1,

FIG. 6 is a right side view of the headrest mount for electronic devices shown in FIG. 2; and,

FIG. 7 is a left side view of the headrest mount for electronic devices as shown in FIG. 2.

The broken lines are included for the purpose of illustration only and form no part of the claimed design.

The headrest mount for electronic devices is used for supporting for example a telephone holder on a headrest column of a car.
